UNITED STATES PATENT OFFICE

2,115,463

SUPERHETERODYNE RECEIVER

John Kelly Johnson, Kenilworth, Ill., assignor to
Hazeltine Corporation, Jersey City, N. J., a
corporation of Delaware

Original application May 22, 1934, Serial No.
726,931. Divided and this application July 12,
1935, Serial No. 30,999

6 Claims. (Cl. 250—20)

This invention relates to the reception and selection of modulated carrier signals, and has for its principal objects to facilitate the selection of such signals and to improve the fidelity of reception thereof.

This application is a division of my application, Serial No. 726,931, filed May 22, 1934, for Superheterodyne receiver which issued March 9, 1937 as Patent No. 2,073,344.

10 A radio broadcast signal is ordinarily transmitted on a carrier wave having two side bands of modulation frequencies, which are of about 6 kilocycles in width on either side of the carrier. Under present broadcasting conditions, the different carrier frequencies are allocated at various 15 positions throughout the broadcast range, usually 10 kilocycles apart, and in many instances the side-band frequencies of one signal channel either overlap those of an adjacent signal channel or else closely encroach upon them. In either case, it is difficult, when tuning a radio broadcast receiver to a desired signal in one such channel, to eliminate interference due to signals in the adjacent channels, particularly when such interfering signals are received with a strength comparable to that of the desired signal.

20 Operation without interference in such cases ordinarily requires that the selecting system shall pass a considerably narrowed band of frequencies so that passage of the interfering signals is substantially prevented. Narrowing the selected band in this manner ordinarily impairs the fidelity of reception of the signals, since the side-band frequencies corresponding to the higher audio 25 frequencies of modulation are suppressed.

It is well known that in the operation of superheterodyne receivers, there is produced an intermediate-carrier frequency which is equal to the difference between the signal-carrier frequency 30 and the local oscillator frequency. This intermediate, or difference, frequency is ordinarily maintained constant over the tuning range of the signals by operating the signal-selecting circuits and the oscillator frequency-determining 35 circuit by a unicontrol device to maintain the constant difference. The two side bands of modulation which extend on either side of the signal-carrier frequency likewise extend on either side of the intermediate-carrier frequency. It is the usual practice in the case of superheterodyne 40 receivers to locate the principal band-width-determining circuits in the intermediate-frequency portion. Hence, the narrowed band width mentioned above is passed by a highly selective intermediate-frequency selective system.

According to one of the features of the invention described in my above-identified patent, No. 2,073,344, it is proposed to improve the fidelity of reception and yet maintain the narrowed band selective characteristic of the selective circuits. 5 This is accomplished by utilizing in a superheterodyne type of receiver a local oscillator system provided with means for shifting the oscillator frequency relative to the signal frequency.

In accordance with this invention, there is provided a selective system which is adjustable to pass any band width between a moderately selective width and a more highly selective width. The adjustable feature is provided by varying the coupling between a pair of coupled tuned 10 circuits, and simultaneously varying the resistance introduced into at least one of these tuned circuits. Since a change of resistance in a tuned circuit also changes the gain, or transmission efficiency, the varying coupling is arranged to 15 automatically maintain the transmission efficiency substantially constant while the resistance is being changed.

Another feature of the above-identified Patent No. 2,073,344, resides in a cooperation between 25 the two foregoing features, in accordance with which means is provided for simultaneously shifting the local oscillator frequency and varying the selectivity of the tuned selecting system.

Fig. 1 illustrates a superheterodyne radio receiver embodying all the features of this invention;

Fig. 2 illustrates graphically the expansion of the band selected by a tuned coupling system according to the invention; and

Fig. 3 shows the impedance variation of one of the circuits of the tuned coupling system in passing to the expanded condition.

Fig. 1 illustrates a superheterodyne receiver comprising in tandem in the order named: an 40 antenna 10 and ground 11; a radio-frequency amplifier 12; an oscillator-modulator 13; an intermediate-frequency amplifier 14; and a detector and audio-frequency amplifier, and loudspeaker 15. The devices 12 to 15 are indicated 45 only in generalized block form since they constitute no part of this invention.

There is arranged according to this invention an intermediate-frequency coupling system 32, connected between the output of intermediate-frequency amplifier 14 and the detector and audio-frequency amplifier, and loudspeaker 15. Means is associated with this coupling system to permit the width of the band transmitted thereby to be varied to change the selectivity and fidelity. 55

This means may be used in conjunction with the oscillator frequency-shifting arrangement of my said copending application. The coupling system 32 comprises a primary coil 33 electromagnetically coupled to a secondary coil 34. The coil 33 is tuned to the intermediate-carrier frequency by a condenser 35, and coil 34 is likewise tuned to the intermediate-carrier frequency by a condenser 36.

- 10 There is arranged in series between the lower ends (the low potential ends) of coil 34 and condenser 36 an arrangement of a coil 37 and a voltage divider comprising two resistors 38 and 39. A switch 40 is provided to connect coil 37 across either resistor 38 or 39 according to whether switch 40 makes contact with switch-point 41 or switch-point 42. The coil 37 is electromagnetically coupled to primary coil 33. The voltage divider contact arm 43 is connected to a point 44, and, when in the neutral position, makes contact with the neutral point 45 between the two resistors. In this position, the low potential ends of coil 34 and condenser 36 are directly connected. The switch 40 is correlated to potentiometer arm 43 so that when the arm 43 is operating on resistor 38, switch 40 makes contact with point 41; but when arm 43 is operating on resistor 39, switch 40 makes contact with point 42.

As arm 43 is moved in either direction from the neutral position, along resistor 38 or resistor 39, more voltage is introduced into the secondary circuit from the coupling between coils 37 and 33, since the voltage across coil 37 also appears across the voltage divider resistance. At the same time, more resistance is introduced in the secondary circuit from the voltage divider. The amount of coupling and resistance increase in the resonant secondary circuit depends upon how far the arm 43 is moved from neutral.

40 It is well known that when the coupling between a pair of coupled tuned circuits is small, the resonance characteristic of the system is sharp. But when the coupling is increased above the "optimum" value, the system becomes characterized by two resonances which become spread apart, thus increasing the selected band width. The term "optimum" coupling means that degree of coupling between the two tuned circuits which produces the maximum amplification at but a single resonant frequency.

50 In this manner, then, the selected band is expanded by movement of the arm 43. The secondary circuit would be characterized by two pronounced resonant peaks, when in the expanded condition, if it were not for the resistance which is introduced. The effect of simultaneously introducing resistance and increasing the coupling is to expand the band without producing objectionable resonance peaks in the secondary circuit.

60 The double-tuned coupling system 32 is adjusted so that when arm 43 is in the neutral position (no resistance being introduced), the selectivity is quite sharp. A typical selectivity curve for this condition is curve E of Fig. 2, which is a graph of attenuation plotted against frequency. In the example illustrated, the intermediate-carrier frequency is 175 kilocycles. The selectivity represented by curve E is such as to pass a band about 4 kilocycles in width; that is, each side band passed is 2 kilocycles in width, for a carrier frequency of 175 kilocycles.

70 While the characteristic represented by curve E provides high selectivity, the fidelity is poor. To improve the fidelity, then, the voltage divider arm

43 is moved from the neutral position to increase the coupling and to introduce resistance into the tuned circuit, as explained above. When the arm 43 is rotated the maximum distance in one direction or the other, the transmission characteristic takes the form of curve F in Fig. 2. According to curve F, coupling system 32 selects a band about 8 kilocycles in width, from 171 to 179 kilocycles.

5 If it were attempted to expand the band by the addition of resistance alone, the characteristic would take a form somewhat like curve G of Fig. 2. Curve G shows greater attenuation than curve E within the band, this being due to the reduction of transmission efficiency because of the added resistance. Curve F, however, shows less attenuation than curve G, and shows about the same attenuation as curve E. The difference in attenuation between curves G and F is made up by the additional coupling due to coil 37. Thus the 10 gain due to coupling coil 37 compensates the loss due to the resistance.

15 It should be understood that the arrangement of the invention is readily susceptible to many variations from the specific embodiment described. For example, if it be found that the primary circuit 33, 35 can stand being loaded by both resistors 38 and 39 in parallel, the switch 40 may be dispensed with and a permanent connection may be made between points 41 and 42 and the point to 20 which the switch is shown connected.

25 There is associated with the receiver a system of automatic volume control. This system comprises a path 46 between a point 47 of coil 33 and a point 48 which is connected to the signal grid 35 circuits of tubes of the intermediate-frequency amplifier 13. There is included in the path 46 automatic volume control apparatus designated generally by the block 50. This automatic volume control apparatus may be of any conventional 40 form which ordinarily includes a rectifier for developing a unidirectional voltage which biases the grids of tubes of the amplifier 13 inversely with any change of the intermediate-frequency voltage at coil 33 and suitable filters.

45 This arrangement, in addition to automatically controlling the volume output, produces the desirable effect of maintaining a substantially uniform output with expansion. This effect is due to the manner in which the impedance of the 50 primary circuit 33, 35 changes in shifting from the contracted to the expanded condition of coupling system 32.

55 Impedance characteristics of the primary circuit 33, 35 are illustrated in Fig. 3 in which the impedance is plotted against the intermediate frequency. Curve K illustrates the relatively sharp impedance curve obtained when the band passed by the coupling system is contracted by placing the arm 43 in the neutral position. When 60 the band passed by the coupling system is expanded, as by moving the arm 43 in either direction, and the coupling between the primary and secondary circuits of the coupling system thereby increased, the impedance at the primary 65 circuit becomes characterized by the double resonance effect due to over-optimum coupling. The impedance of the primary circuit under the expanded condition is shown by curve L, from which it is observed that there are two pronounced resonant peaks and a dip between them at the carrier frequency. The reason for the pronounced peaks at the primary circuit while such peaks are absent at the secondary circuits 70 75

lies in the fact that no additional resistance is introduced into the primary circuit when the coupling is increased.

Since the voltage applied to the automatic volume control apparatus is taken from the primary circuit, the automatic volume control effect is caused to relax when the band width selected by coupling system 32 is expanded. The reason for this is that the intermediate-carrier frequency lies within the dip in curve L. In consequence the volume output rises somewhat when the band width is expanded; or, in other words, the sensitivity would be somewhat less in any except the expanded condition.

15 This counteracts the tendency for the volume to drop due to the moving of the carrier to one side of the sloping resonance characteristic and thus decreasing in amplitude as the band is expanded. This also compensates for the net drop 20 in output which results from the cutting off of a large portion of one of the side bands.

If the receiver is tuned in the expanded condition, this primary impedance characteristic produces a noise suppression and sharp tuning effect.

25 On either side of the exact resonance frequency the voltage actuating the automatic volume control is abnormally high, thus decreasing the receiver gain, while at exact resonance the automatic volume control voltage is abnormally low.

30 This condition produces a rapid and easily distinguished output volume rise when tuning through resonance, which indicates the exact point at which the receiver is correctly tuned.

What is claimed is:

35 1. A carrier-frequency coupling system adapted to select a band of frequencies including a carrier frequency and associated sidebands, comprising a pair of coupled circuits, each of which is tuned to said carrier frequency, and means for increasing the width of said band which comprises auxiliary means coupling said circuits, an adjustable resistance element connected in circuit with said auxiliary means and having at least a portion thereof effectively included in one 40 of said circuits, and means for adjusting said element to increase the resistance of said one of said circuits and simultaneously to increase the coupling between said circuits by said auxiliary means.

50 2. A carrier-frequency coupling system adapted to select a band of frequencies including a carrier frequency and associated sidebands, comprising a pair of coupled circuits each of which is tuned to said carrier frequency, means for expanding said band which comprises an auxiliary element included in a first of said circuits and coupled to the second of said circuits, and a resistance voltage divider including an adjustable contact arm, connected in circuit with said auxiliary element and having at least a portion thereof effectively included in said first circuit, adjustment of said arm being effective to increase the amount of resistance included in said first circuit and simultaneously to increase the coupling

between said first and second circuits due to said auxiliary element.

3. A carrier-frequency coupling system adapted to select a band of frequencies including a carrier frequency and associated side bands, comprising a transformer having a primary and a secondary coil each of which is tuned to said carrier frequency by capacity, and an auxiliary coil, shunted by a voltage divider, in series with one of said transformer coils and its associated capacity, said auxiliary coil being coupled to the other of said coils, whereby adjustment of said voltage divider changes the resistance in the circuit of said one of said coils and also changes in the same direction the coupling between the circuits of said primary and secondary coils.

4. A carrier-frequency band-selecting system comprising primary and secondary circuits electromagnetically coupled, each of said circuits being tuned to said carrier frequency, an auxiliary coil included in said secondary circuit and coupled to said primary circuit, and a voltage divider connected across said auxiliary coil and including a contact arm adjustable to vary the coupling due to said auxiliary coil and simultaneously to vary the resistance introduced into said secondary circuit in the same sense, whereby the selected band may be expanded by increasing the coupling and the resistance in said secondary circuit.

5. A carrier-frequency band-selecting system comprising primary and secondary circuits electromagnetically coupled, each of said circuits being tuned to said carrier frequency, an auxiliary coil included in said secondary circuit and coupled to said primary circuit, a voltage divider having two connected resistors and a movable contact arm which when in the neutral position contacts with a point between said resistors, switching means for connecting either one or the other of said resistors across said auxiliary coil, and means for automatically operating said switching means to connect across said coil whichever resistor said contact arm makes contact.

6. In a radio receiver, a carrier-frequency band-selecting system comprising a primary and a secondary circuit coupled together, each of said circuits being tuned to the carrier frequency, means for increasing the coupling between said circuits and for simultaneously increasing the resistance introduced into said secondary circuit, whereby when said coupling is increased the selected band width is expanded and said primary circuit becomes characterized by pronounced resonance peaks near each side of said selected band but said secondary circuit remains substantially free from resonance peaks, and an automatic volume control arrangement for controlling the output of said receiver, the input of said arrangement being connected to said primary circuit, whereby the automatic volume control effect relaxes when the selected band width is expanded.

JOHN KELLY JOHNSON.
